APPLYING FILMS

William Earl, Brooklyn, and George W. Fleischman, Astoria, N. Y., assignors to E. R. Squibb & Sons, New York, N. Y., a corporation of New York

Application November 23, 1937, Serial No. 176,010

12 Claims. (Cl. 91—47)

This invention relates to applying films of various substances, especially mobile and viscous liquids, to the lip—i. e. the upper edge, or top surface, of the mouth or neck—of containers.

5 It has been found necessary or desirable in certain industries to apply various substances to container lips. Thus, in packing pharmaceuticals deleteriously affected by the atmosphere, or as a means of insuring against leakage of the contents, it is advantageous to employ, as a sealing means auxiliary to the regular screw-cap or similar closure, a disc of paper, Cellophane, or some other suitable material which seals the bottle and is not affected by the contents of the bottle 10 when cemented to the container lip (as shown in U. S. Patent No. 1,966,273). According as this disc is or is not gummed or provided with a ring of adhesive, the bottle lip must first receive a film of water (or of a volatile solvent for the 15 cement), or a film of adhesive, respectively. Then the cap, the disc having been placed therein, is attached to the container by the customary appliance; and the disc, being brought into tight contact with the lip, adheres thereto.

20 A contrivance heretofore proposed for applying such water or adhesive to container lips consists of a rotating roller with its axis horizontal, fixed at such a distance above the container conveyor as to make the required deposit on the lips of 25 containers of average height. Since, however, a considerable proportion of commercial-run bottles or other containers deviate from the average height, serious difficulties attend the use of this contrivance; when a container shorter than the 30 average passes under the roller, it may receive no liquid or adhesive whatever; and a tall container may either have a quantity of fluid or adhesive scraped into its mouth and its contents contaminated thereby and/or it may cause the machinery to be jammed.

35 It is the object of this invention to provide an improved method of and apparatus for the application of films of various substances to the lips of containers. More particularly, it is the object 40 of this invention to provide a method and mechanism whereby films of various substances, especially mobile and viscous liquids, adhesives, or cements, may be efficiently and evenly applied in a predetermined amount to the lips of containers, the mechanism being adapted to compensate automatically for differences in container heights and being characterized by other features of 45 superiority in structure and operation.

50 The method of this invention essentially comprises continuously moving containers into op-

erative position, and alternately picking up a uniform charge of a film substance and applying it to a container lip while the container is in motion, the application being effected evenly and substantially without wiping contact. The apparatus of this invention essentially comprises 5 means for continuously moving containers into operative position, applicators adapted alternately to pick up a uniform charge of the film substance and to carry it into operative position 10 synchronously with the containers, and means for actuating the applicator while in operative position to apply the charge evenly to a container lip substantially without wiping contact; and 15 also means for automatically compensating for differences in container heights.

A preferred embodiment of the invention is illustrated in the accompanying drawings, wherein:

Fig. 1 is a top view of apparatus embodying the 20 invention;

Fig. 2 is a side view of the apparatus of Fig. 1, with the reservoir shown partly in section;

Fig. 3 is a vertical sectional view of the applicator mechanism in operative position on an 25 average container; and

Fig. 4 is a vertical sectional view of the applicator mechanism in operative position on a shorter container.

In the apparatus illustrated, a conveyor 33 (for 30 convenience of illustration shown as linear) carries containers 34 into operative position (the position of the middle container in Figs. 1 and 2). Situated thereover is an applicator carrier 45, rotatable on vertical standard 10, and a cam support 11, 12, fixed on said standard 10. The applicator carrier rotates counter-clockwise in Fig. 1 and is synchronized with the container conveyor (moving from left to right) so that at a point of coincidence of the applicator and container 35 paths an applicator is situated in operative position directly over a container lip. The applicator carrier 45 comprises arms 15 to the distal ends of which are attached the applicators. Each applicator consists of a shank 16 vertically reciprocable in arm 15 (Figs. 3 and 4); and having a narrow upper longitudinal bore 17 connecting at shoulder 18 with a wider longitudinal bore 19; a spiral spring 20 girdles shank 16 and is confined between arm 15 and flange 21 on shank 16, acting to force the shank upwards; a key 91 in shank 16 slides in slot 9 in arm 15 and serves to prevent rotation of the shank; a plunger 22 extends through bores 17 and 19 and has its downward movement limited by the head of a screw 23 in 50 55

the top of the plunger; a spiral spring 24 girdles plunger 22 and is confined between shoulder 18 and a flange 25 on the plunger, serving to force the plunger downwards; a plate 26 is attached to 5 the bottom of plunger 22 and has affixed thereto an annular dauber 27 of resilient material, such as rubber; and an extension 28 on flange 21 carries a cam follower 29. Cam support 11, 12 has fixed to the distal ends thereof arcuate cams 13 and 14 (Figs. 1 and 2) situated respectively over 10 a film-substance reservoir and the operative position. The film-substance reservoir (Figs. 1 and 2) consists of a reservoir 30 containing film substance 31 in which is partly immersed a feeder cylinder 32 rotating on a horizontal axis. The feeder cylinder may be rotated synchronously 15 with the other mechanisms.

The operation of the apparatus described is as follows: Containers are fed upon the continuously moving conveyor in spaced vertical positions and consecutively pass into operative position under an applicator, the applicator carrier being synchronously actuated with the conveyor. As 20 the applicators are rotated, each in turn passes first under cam 13 (which causes shank 16 and dauber 27 to be depressed to pick up a charge of 25 a film substance, such as an adhesive, from feeder cylinder 32) and then under cam 14 (which again depresses dauber 27 through shank 16 to deposit 30 the charge of film material on the lip of a container on the conveyor). The contact between the dauber and container lip is essentially a striking contact (i. e. substantially without wiping 35 contact) since in operative position the container path is tangential to that of the dauber and they consequently move in the same direction and at the same speed. Obviously, wiping contact may be completely avoided by utilizing an arcuate conveyor, i. e. one in which the containers travel 40 in at least a small arc coincident with the arc of the dauber path. The feed cylinder 32 is partially immersed in film substance in the reservoir, and has its uppermost portion in the same plane as the shortest containers encountered; the cylinder is synchronously actuated 45 with the applicator mechanism so as to avoid wiping contact with the daubers and thereby feed an even, uniform charge thereon. The applicator mechanism is so adjusted that when shank 50 16 is forced down by cam 14, the dauber will positively contact the lip of the shortest container encountered without compressing plunger spring 24, as shown in Fig. 4; spring 24 then automatically compensates for all taller containers by yielding as much as necessary, as shown in Fig. 3. The film substance is thus evenly applied to the 55 lips of all containers within the range of heights for which adjustment has been made.

The invention may be variously otherwise embodied—as by varying the number of applicators on the carrier, or by using other mechanism for conveying containers or for feeding adhesive or the like or for compensating for different container heights—within the scope of the appended 60 claims.

We claim:

1. Apparatus for applying films of a substance to the lips of containers comprising means for 65 moving containers into operative position, applicators adapted alternately to receive a uniform charge of the film substance and to carry it into said operative position synchronously with the containers, and means for actuating the applicators while in said operative position to apply 70

the charge to a container lip substantially without wiping contact.

2. Apparatus for applying films of a substance to the lips of containers comprising means for moving containers into operative position, applicators adapted alternately to receive a uniform charge of the film substance and to carry it into said operative position synchronously with the containers, means on said applicators automatically compensating for variations in the height 5 of the containers, and means for actuating the applicators while in said operative position to apply the charge to a container lip substantially without wiping contact.

3. Apparatus for applying a liquid film to the 15 lips of containers comprising a continuously moving conveyor for the containers, a rotary applicator carrier arranged so that the paths of the applicators thereon and of the containers have at least one point of coincidence, and means for 20 alternately causing said applicators to pick up a uniform charge of the liquid and deposit it on the lip of a container while at the point of path coincidence.

4. Apparatus for applying a liquid film to the 25 lips of containers comprising a continuously moving linear conveyor for the containers, a rotary applicator carrier arranged so that the paths of the applicators thereon and of the containers have at least one point of coincidence, and means for 30 alternately causing said applicators to pick up a uniform charge of the liquid and deposit it on the lip of a container while at the point of path coincidence.

5. Apparatus for applying a liquid film to the 35 lips of containers comprising a continuously moving conveyor for the containers, a rotary applicator carrier arranged so that the paths of the applicators thereon and of the containers have at least one point of coincidence, the applicators 40 consisting of resilient daubers having spring means for compensating for variations in the height of containers, and means for alternately causing said applicators to pick up a uniform charge of the liquid and deposit it on the lip of 45 a container while at the point of path coincidence.

6. Apparatus for applying a liquid film to the lips of containers comprising a continuously moving linear conveyor for the containers, a rotary applicator carrier arranged so that the paths of 50 the applicators thereon and of the containers have at least one point of coincidence, a reservoir for the liquid having a feeding cylinder, and means for alternately causing each applicator to contact with the feeding cylinder and then with 55 the lip of a container while at the point of path coincidence.

7. An apparatus of the type described comprising a conveyor, sequentially spaced containers on the conveyor, an applicator, means for periodically positioning the applicator above the mouth of each of the subjacent moving containers and for synchronizing the rate of movement of the applicator and an immediately associated container for a portion of their conjoint travel, and 60 means for pressing the applicator upon the lip of the container during their synchronized movement.

8. An apparatus for applying a substance to the 65 lips of containers comprising a conveyor adapted to carry containers at spaced intervals, a rotatable member, applicators on the periphery of said member sequentially registering with and overlying the lips of the immediately subjacent containers for a portion of their travel, and means 70

for pressing the registering applicator upon the container lip.

9. An apparatus for applying a liquid to the lips of containers comprising a conveyor adapted to carry containers at spaced intervals, a plurality of spaced applicators successively movable into operative position over the lips of the containers on the conveyor, and means for sequentially pressing the applicators into contact with the container lips.

10. In a device for applying substances to container lips, a vertically reciprocable shank, a spring pressing it upward, a plunger extending through the shank, a dauber attached to the bottom of the plunger, and a spring pressing the plunger downward.

11. In a device for applying liquids to container lips, a fixed cam, a revolving vertically recipro-

cable shank actuated by the cam, a spring pressing the shank upward, a plunger extending through the shank, a dauber attached to the bottom of the plunger, and a spring pressing the plunger downward.

12. An apparatus comprising a vertical standard, a rotating carrier supported thereby and having a plurality of arms, a vertically reciprocable shank carried at the distal end of each arm, a spring pressing the shank upward, a plunger extending through the shank, a dauber attached to the bottom of the plunger, a spring pressing the plunger downward, a cam supported by the standard above the rotating carrier and adapted to actuate the shank.
